UNITED STATES PATENT OFFICE.

NEWTON L. SCHLOSS, OF NEW YORK, N. Y.

DESIGN FOR AN ELEVATOR-SIGNAL-LIGHT BOX.

42,677.

Specification for Design.

Patented June 25, 1912.

Application filed April 19, 1912. Serial No. 691,958. Term of patent 7 years.

To all whom it may concern:

Be it known that I, NEWTON L. SCHLOSS, a citizen of the United States, residing in the borough of Manhattan, city, county, and State of New York, have invented a new, original, and ornamental Design for an Elevator-Signal-Light Box, of which the following is a specification, reference being had to the accompanying drawing, forming a part thereof.

The figure shown in the drawing is a perspective view showing my new design.

I claim as my invention:

The ornamental design for an elevator signal light box, as shown.

NEWTON L. SCHLOSS.
